UNITED STATES PATENT OFFICE.

JAMES M. THOMSON, OF SAN FRANCISCO, CALIFORNIA.

FOLDING GAFF-HOOK.

No. 895,126.

Specification of Letters Patent. Patented Aug. 4, 1908.

Application filed November 18, 1907. Serial No. 402,671.

To all whom it may concern:

Be it known that I, JAMES M. THOMSON, a citizen of the United States, and a resident of the city and county of San Francisco and State of California, have invented an Improved Folding Gaff-Hook, of which the following is a specification.

This invention has for its object to provide an improved gaff-hook having several novel features of construction and several advantages in its operation that adapt it more particularly for the use of anglers and sportsmen.

The improvements embraced in and comprising my said invention consist in a staff composed of jointed and folding sections or members having means for locking or fixing the sections rigidly at the joint, such means being automatic or self-operating at the moment that the staff is unfolded and the sections are brought in line.

The improvements consist further in a movable guard for the point of the hook, so arranged on the end of the handle-portion of the staff that when the sections are folded together the point of the hook which is mounted on one end of the staff will be brought over and in line with the guard, and the latter will be retained in position covering and protecting the point of the hook; or a short movement of the guard on the butt end of the staff will release the hook and allow the sections of the staff to separate and come into line.

The nature of the said improvements and the manner in which I proceed to apply and carry out the same in the production of my folding gaff-hook, are explained at length in the following description, wherein the accompanying drawing forming part of this specification is referred to by figures and letters.

Figure 1 of the drawings illustrates my improved gaff-hook folded for carrying. Fig. 2 is a view representing the position of the parts after the guard has been drawn down against its retaining-spring, releasing the hook from the guard and allowing the sections to open out in a straight line. Fig. 3 represents the gaff-hook ready for use. Figs. 4 and 5 are longitudinal sectional views, on an enlarged scale, of the self-locking means at the joint, and the guard on the butt end of the staff.

A novel feature in the folding-gaff of my invention consists in a self-acting coupling so arranged and operated that when drawn

away from over the joint by hand, it will be held out of active position as long as the sections of the staff remain folded, but at the moment that the sections are opened out and brought in line, the coupling will automatically move into position and lock the joint. The preferred form or construction of this self-acting locking-means, which I have illustrated in the drawings, comprises a slidable sleeve or ferrule *f* sufficient in length to cover the joint *d* that unites the sections *a*—*b* of the staff, and of proper diameter to slide smoothly and yet fit closely upon the staff-sections. A cross-pin *2* passing through a slot 3 in the staff-section *a* limits the movement of the sleeve *f*, and also furnishes a bearing point for one end of a coiled-spring *h* which is inclosed within the staff-section. The members *a*—*b* are formed of metal tubing for the purpose of combining the desired lightness with the necessary strength and stiffness. The guard on the butt end of the staff is best formed of a ferrule *g* loosely fitted on the staff-section, so as to slide readily on it, and limited in its movement by a stop-pin *6* that passes through and is fitted to slide in a slot 7 in the staff-section. The ferrule *g* carries on the end a boss or head 8 in which is a hole or recess 9 of proper size to admit the point of the hook *e*, when the latter is brought in position in line with such aperture by folding the hook-bearing section *b* of the staff over, against or upon the guard-bearing section *a*, as illustrated in Fig. 1. In that position the guard covering the point of the hook *e* is held by a coiled-spring located within the hollow staff-section, and so arranged as to press the guard towards the end of the tube and maintain it normally in that relation; but a sufficient length of sliding movement on the tube is afforded for drawing back the guard until the point of the hook is uncovered and freed from the guard.

By referring to Figs. 3, 4 and 5, it will be seen that the same spring *h* can be readily utilized both for the guard *g* and for the locking-sleeve, simply by employing a spring of sufficient length and power to act on the guard *g* at one end of the staff, and on the locking-ferrule *f* at the joint; the ends of the spring being arranged for that purpose to bear against the cross-pin *6* at the guard, and the cross-pin *2* of the locking-ferrule.

The folding-gaff of my invention as thus constructed, has the advantage of being

readily unfolded and set up for use in an instant with one hand, leaving the angler free to handle the fishing-rod with the other hand.

- 5 To open the staff and set up the gaff-hook for use, from its folded state as represented in Fig. 1, the angler will place the joint-bearing end against his knee, or some other convenient stationary object, and pressing 10 down the guard on the butt end with the same hand in which he grasps the staff-section, he will release the point of the hook from the guard, and thereby free the hook-bearing section from the handle-section. 15 At the moment of its release from the guard, the hook-bearing section will drop away from the section in the grasp of the angler's hand, until the sections assume a straight line, whereupon the slide will slip 20 over the joint and lock the same by virtue of the spring acting against the slide in the proper direction. The staff-sections are thus locked rigidly and in line one with the other at the instant that one comes in line with the 25 other, without any attention or movement on the part of the operator, thus providing an automatic locking means of great convenience.

Having thus described my invention, what

30 I claim is:—

1. A gaff-hook comprising a folding-staff having two sections united by a hinge-joint, a locking-means at the joint operating to hold the sections rigidly when opened and set 35 in line, a hook on the end of one section and a

guard on the end of the other section movable thereon, and adapted in one position to engage the point of the hook and thereby retain the staff-sections in a folded state, and in another position to release the hook-bearing section.

2. A gaff-hook comprising a folding staff having a hook-bearing section and a handle-bearing section united by a hinge-joint, a locking-means at the joint comprising a slide-able member adapted in one position to extend over the hinge-joint and thereby hold the members in line, a spring acting to normally hold such slideable member in locking position, a hook on the end of one staff section, and a slideable guard on the end of the handle-section adapted to engage the point of the hook when the said sections are placed in the folded relation.

3. The combination with the staff-sections united by a hinge-joint, of a slideable-member adapted to normally set over the hinge-joint on opposite sides of its pintle, and thereby hold the staff-sections rigidly in line, a spring operating to retain the said slideable member in such locking-position, a hook on the end of one section, and a slideable-guard on the other section adapted to engage the said hook and thereby retain the sections in folded relation.

JAMES M. THOMSON.
